UNITED STATES PATENT OFFICE.

JOHN HUMPHRIES, OF KIDDERMINSTER, ENGLAND.

DESIGN FOR A CARPET-PATTERN.

Specification forming part of Design No. 5,903, dated June 4, 1872.

To all whom it may concern:

Be it known that I, JOHN HUMPHRIES, of Kidderminster, Worcestershire, in England, have invented a new and original Design for Carpets; and I do hereby declare that the following is a full, clear, and exact description thereof, which will enable others skilled in the art to make and use the same, reference being had to the accompanying photographic illustration forming part of the specification.

The nature of my design is fully represented in the accompanying photographic illustration, to which reference is made.

This invention relates to a rectilinear design for carpets, which contains rows of ornamental figures, there being in the present design two

several kinds of such figures. One of these has a square inner figure with ornamental center and outline, and with moss-like growth along the outline. The other figure contains a cross in the middle, and fanciful borders around the same. The outer lines of the two figures are similar to each other, and made to correspond when they are near together, as shown.

I claim as my invention—

The design for carpets, as shown.

JOHN HUMPHRIES.
